John E. Blatchford, 205 Baum St., and Charles E. McBride, 821 W. 9th St., both of East Liverpool, Ohio

Filed Sept. 18, 1961, Ser. No. 66,732

Term of patent 7 years

(Cl. D31—4)

FIG. 1

FIG. 2

FIG. 1 is a top perspective view of a minnow seine, showing our new design;

FIGURE 2 is a side elevational view thereof.

The sides not shown are substantially like the side shown. It is to be understood that the criss-cross pattern partially shown in FIG. 1 is continuous throughout the area.

We claim:

The ornamental design for a minnow seine, as shown and described.
